VALANCE

Albert Packer, 5934 Wrightcrest Drive,
Culver City, Calif. 90230

Filed Apr. 15, 1966, Ser. No. 1,906

Term of patent 14 years

(Cl. D21—6)

FIG. 1 is a front elevational view of a valance showing my new design, the right festoon being identical in appearance to the left festoon and a portion thereof shown broken away for convenience of illustration.

FIG. 2, to a reduced scale, is a cross-sectional view taken on the line 2—2 of FIG. 1.

The dominant features of the design are shown in full lines. The top of the valance is plain and unornamented.

I claim:

The ornamental design for a valance, substantially as shown and described.
